UNITED STATES PATENT OFFICE

ANTHONY GEORGE MALDON MICHELL, OF MELBOURNE, VICTORIA, AUSTRALIA, AS-
SIGNOR, BY MESNE ASSIGNMENTS, TO MICHELL-CRANKLESS ENGINES CORPORA-
TION OF NEW YORK, N. Y., A CORPORATION OF NEW YORK

GEARING FOR ACTUATING SLEEVE VALVES FOR CRANKLESS ENGINES

Application filed December 27, 1926, Serial No. 157,377, and in Great Britain January 19, 1926.

The present invention relates to gearing for actuating valves of crankless internal combustion engines, that is to say, engines of the type in which the axes of the cylinders of the engine are parallel to the axis of the main shaft, the valves being of the sleeve type coaxial with the cylinders and being actuated with a combined rotary and reciprocating motion.

Such valves are well-known, and are operated by various means, an appropriate motion being communicated to the valve to cause a port or ports cut through the side of the sleeve to register with ports in the cylinder as required for the admission and exhaust of the working fluids of the engine.

The motion applied to said valves has in some cases been a simultaneous rotary and reciprocating movement and the present invention refers specifically to valves of that type.

According to the present invention the means employed for imparting continuous rotary motion of the valve about its axis simultaneously with a reciprocating motion in the direction of its axis consists of a novel mechanism involving a new mechanical movement which in practice is highly efficient at high speeds and the mechanical form of which is extremely simple.

Briefly stated the mechanism for the purpose stated comprises an oblique annular element formed upon the valve which element is in geared engagement with a rotary element imparting positive rotation to the valve and in conjunction with said geared element lateral faces are provided on the oblique element which have constant rolling engagement with faces located in a fixed plane which latter engagement causes reciprocation of the valve parallel to its axis simultaneously with said rotary motion consequent upon the obliquity of said annular element.

The invention will now be further described with reference to the accompanying drawings illustrative of a practical application of the same. The type of engine shown in these drawings is the known crankless or slant type, but it is to be understood that the invention is not restricted thereto as it is

equally applicable to other types of engines wherein a sleeve valve is associated with a port or ports in the engine cylinder or cylinders.

In these drawings Figure 1 is a partial longitudinal section though the axes of the main shaft and of a cylinder of a crankless engine, the valve being shown in position in the cylinder but not in section.

Figure 2 is a transverse section showing the cylinder and valve illustrated in Figure 1, together with parts of other similar cylinders and valves combined therewith in one engine.

The cylinder 1, shown in Figure 1, which is fitted with a cylinder head 2, contains the sleeve-valve 3, constructed according to the present invention, and the piston 4. The piston has attached to it the yoke 5, carrying the slippers 6, by which it co-acts with the slant 7, mounted on the engine-shaft 8, and the shaft 8 is fitted with a thrust collar 9, abutting against a fixed thrust bearing 10 which prevents endwise motion of the shaft. All these parts are according to a known construction.

Upon the shaft 8 is rigidly mounted the pinion 11 which constantly meshes with and drives the gear wheel 13 rigidly secured on the valve 3. This gear wheel 13 is concentric with but oblique to the axis of the valve 3, and has formed thereon bevelled lateral faces 14 which are in continuous rolling engagement with the coned faces of the collars 12 on the sleeve 12a on the shaft 8. These collars 12 are so disposed that no side play can occur in the gear wheel 13.

In the four-stroke internal combustion engine shown in the figures, the wheel 13 has twice as many teeth as the wheel 11 so that the valve 3 rotates at one-half the angular speed of the engine shaft 8.

It will be observed that as the valve 3 revolves, it is compelled, by the engagement of the faces 14 of the gear wheel 13 between the collars 12, to execute a reciprocating motion parallel to its axis, the complete period of this reciprocation being the same as the period of revolution of the valve. During such valve-cycle, the port 15, formed in the

valve sleeve at the pressure end of the cylinder, registers once with the admission port 16 (see Fig. 2) provided in the engine cylinder 1 and once with the exhaust port 17 therein, thus making communication between the interior of the sleeve and cylinder and the latter ports at the respective times required for the operation of the engine.

I claim:—

- 10 1. In an internal combustion engine of the parallel cylinder type, the combination with a sleeve valve for each of the cylinders of means for imparting simultaneous rotary and reciprocating motion to the valve comprising a gear obliquely mounted on the latter, and a pinion on the driving member in mesh with the gear on said driven member.
- 15 2. In an internal combustion engine of the parallel cylinder type, the combination with a sleeve valve for each of the cylinders of means for imparting simultaneous rotary and reciprocating motion to the valve comprising a gear obliquely mounted on the latter having beveled lateral faces, a pinion on the driving member in mesh with the gear on the driven member, and laterally arranged sleeves on the driving member having beveled flanges engaging the lateral faces on said gear.
- 20 3. In a crankless internal combustion engine, the combination of an engine shaft, a series of cylinders having their axes parallel to the axis of the shaft, a reciprocating piston in each cylinder, means actuated by the movements of the pistons for rotating the shaft, sleeve valves interposed between the cylinders and pistons and having ports co-acting with ports in the cylinders, and means for imparting simultaneous rotary and reciprocating motion to said valves comprising a gear obliquely mounted on each valve and a pinion on the engine shaft in mesh with the gears on the valves.
- 25 4. In a crankless internal combustion engine, the combination of an engine shaft, a flat annular member mounted obliquely on the shaft, a series of cylinders arranged around the shaft, pistons in said cylinders operatively connected to said annular member for rotating the shaft, sleeve valves interposed between the pistons and cylinders and having ports co-acting with ports in the latter, and means for imparting simultaneous rotary and reciprocating motion to said valves comprising a gear obliquely mounted on each sleeve, and a pinion on the engine shaft in mesh with the gears on the sleeves.
- 30 5. In a crankless internal combustion engine, the combination of an engine shaft, a flat annular member mounted obliquely on the shaft, a series of cylinders arranged around the shaft having their axes parallel to the axis of said shaft, pistons in said cylinders operatively connected to said annular member for rotating the shaft, sleeve valves interposed between the pistons and cylinders

and having ports co-acting with ports in the latter, and means for imparting simultaneous rotary and reciprocating motion to said valves comprising a gear obliquely mounted on each sleeve having beveled lateral faces, a pinion on the engine shaft in mesh with the gears on the sleeves, and laterally arranged sleeves on the engine shaft having beveled flanges engaging the lateral faces on the gears.

75 6. In an internal combustion engine of the parallel cylinder type, the combination with a sleeve valve for each of the cylinders, of means for imparting simultaneous rotary and reciprocating motion to each of said valves comprising a gear obliquely mounted on each of said valves and a pinion on the engine shaft in mesh with each of the valve gears and lateral guide surfaces arranged in fixed planes through the shaft and engaging lateral bearing faces on each of said valve gears.

80 7. In an internal combustion engine of the parallel cylinder type, the combination with a sleeve valve for each of the cylinders, of means for imparting simultaneous rotary and reciprocating motion to each of said valves comprising a gear obliquely mounted on each of said valves and a pinion on the engine shaft in mesh with each of the valve gears and laterally arranged flanges on said shaft adjacent opposite sides of said pinion and engaging beveled lateral bearing faces on each of the valve gears.

85 Dated this 29th day of November, 1926.
